[57] ABSTRACT

An ion micro-analyzer, wherein a finely collimated ion beam is projected onto the surface of a sample to be analyzed, the projected ion beam repeatedly scans the sample surface while, one time in fixed scanning-frequency intervals, a fixed point on the sample surface is bombarded by the ion beam for a constant time, the image of the secondary electrons from the sample surface is projected on the screen of a Braun tube oscilloscope swept synchronously with the ion beam and observed by performing intensity modulation of the oscilloscope in correspondence with the amount of the secondary electrons emitted from the sample surface, the fixed position on the sample surface bombarded by the ion beam in the way described above is moved to a position for analysis while observing the brilliant point on the image of secondary electrons which corresponds to the fixed point on the sample bombarded by the ion beam, and then a mass-spectroscopic analysis of the secondary ions emitted from the fixed point on the sample surface is done while the fixed position on the sample desired for analysis is bombarded by the ion beam.

ION MICRO-ANALYZER

BACKGROUND OF THE INVENTION

1. Field of the Invention

This invention relates to an improvement of an ion micro-analyzer.

2. Description of the Prior Art

The ion micro-analyzer to be described hereinbelow is a device, wherein a small surface portion (a small area whose diameter is usually about several microns and this portion will be referred to as the analysis point hereinbelow) of a solid-state sample to be analyzed is bombarded by a finely collimated primary ion beam and the composition analysis and the like on the analysis point is obtained by analyzing and/or measuring the secondary radiations (such as secondary ions, secondary electrons etc.) emitted from the bombarded point. In conventional devices, the secondary ions from the analysis point are analyzed by use of a mass spectrometer.

The ion micro-analyzer comprising a mass spectrometer has the advantage that the composition of a small part of a solid-state sample can be analyzed quantitatively with high precision, but conventional devices of this type suffer from the disadvantages that the selection of the small part for analysis (analysis point) is troublesome and that it is difficult to see the relationship between the data obtained by mass-analysis and the position of the analysis point on the sample.

Namely, it is necessary for analysis to select an analysis point properly by considering which position on the sample is most appropriate for analysis and to project the ion beam spot accurately on the analysis point thus selected. In the subsequent process of data analysis, it is necessary to make an accurate correspondence between the data and the analysis point, and thus great care must be taken in making such correspondence.

In a conventional method, the irradiation spot of a primary ion beam on the sample surface is observed with an optical microscope and the irradiation spot is moved to a desired analysis point by suitably adjusting deflection voltages for the primary ion beam. This method is however, laborious due to the need to move the irradiation spot to the analysis point and, moreover, it is impossible to read the position of the analysis point on the optical image of the sample quantitatively so that the relationship between the data and the position of the analysis point becomes obscure. Particularly, when many analysis points on a sample surface are to be analyzed in series, it becomes difficult to distinguish which datum corresponds to a particular analysis point. Thus, not only is the data analysis laborious and time-consuming, but also errors in data analysis may easily occur.

In another conventional method, only such ions having a specific mass-to-charge ratio (m/e value) among the secondary ions emitted from the sample surface are analyzed and measured with a mass spectrometer by planely scanning the primary ion beam radiated on the sample surface, the output signal is added to the terminal for intensity modulation of a Braun tube oscilloscope swept synchronously with the scanning of the primary ion beam to display the image of secondary ions (the distribution of the specified secondary ion beam described above) from the sample surface on the screen of the Braun tube, and thus the state of the sample may be observed before analysis. In this method,

however, the distribution of only such elements corresponding to the secondary ions having the specified m/e value is displayed so that the state of the sample surface region not including the above elements or the distributions of the other elements in the sample cannot be observed. Thus, it is impossible to obtain information sufficient for the selection of an analysis point. Further, it is impossible to perform an analysis while displaying the image of the secondary ions from the sample surface on the screen of a Braun tube. In other words, the irradiation spot of the primary ion beam must be fitted and fixed to a desired analysis point for analysis, but this process cannot be performed when the image of the secondary ions is displayed (or when the primary ion beam is scanned). Conversely, when a mass-spectroscopic analysis is done for a particular analysis point, the sample surface cannot be observed. Thus, it is difficult to obtain accurate information on the relationship between the data and the position on the sample.

SUMMARY OF THE INVENTION

This invention is intended to obviate the deficiencies described hereinabove, and a primary object of this invention is to provide an improved ion micro-analyzer, wherein an irradiation spot of a primary ion beam can be made to strike accurately on a desired analysis point and a mass-spectroscopic analysis of the analysis point can be achieved while observing the surface of a sample for analysis.

A second object of this invention is to provide an improved ion micro-analyzer, wherein the relationship between the analysis data and the analysis point can be accurately determined.

In order to achieve the primary object described above, the ion micro-analyzer according to this invention is characterized in that the primary ion beam irradiating a sample surface is scanned at a plane angle, the secondary electrons emitted from the sample surface by ion bombardment are detected, and the detected signal is added to a terminal for intensity modulation by a Braun tube oscilloscope swept synchronously with the scanning of the primary ion beam to display the image of secondary electrons corresponding to the sample surface on the fluorescent screen of the oscilloscope; the brilliant point corresponding to the fixed position of the irradiation spot of the primary ion beam is displayed on the image of secondary electrons by fixing the irradiation spot of the primary ion beam at an arbitrary point on the sample surface for a constant time interval during scanning; the irradiation spot is made to strike accurately on a desired analysis point by adjusting the deflection voltage of the primary ion beam while observing the position of the brilliant point; and the secondary ions, emitted from the analysis point while the irradiation spot of the primary ion beam is fixed on the desired analysis point, are analyzed and measured with a scanning-type mass spectrometer.

The second characteristic of this invention for achieving the second object of this invention described above lies in that not only the data obtained by mass spectroscopy, but also the position of the corresponding analysis point is recorded in the ion micro-analyzer described hereinabove.

Other objects, features and advantages of this invention will become more apparent from the following detailed description of the embodiments of this invention when taken in conjunction with the accompanying drawings.

BRIEF DESCRIPTION OF THE DRAWINGS

FIG. 1 is a block circuit diagram showing the principle of an ion micro-analyzer according to an embodiment of this invention;

FIG. 2 shows a train of waveforms for schematically illustrating the relationship between the ion beam scanning signal in the ion micro-analyzer shown in FIG. 1 and the output signal;

FIG. 3 is a schematic diagram showing the relationship between the image of secondary electrons from the sample surface displayed on a Braun tube oscilloscope and the deflection voltage for the ion beam;

FIG. 4 shows a train of waveforms for schematically illustrating the relationship between the deflection voltage for an ion beam in analysis, the mass scanning signal and the output signal from an ion collector;

FIG. 5 shows a table indicating an example of analysis data recorded by a printer;

FIG. 6 shows a train of waveforms for schematically illustrating the relationship between the ion beam scanning signal, the instruction signal for analysis, the mass-scanning signal and the ion collector output signal when the irradiation spot of an ion beam is made to lie at a desired analysis point and a mass-spectroscopic analysis of the analysis point is done; and

FIG. 7 shows a train of waveforms for schematically illustrating the relationship between various signals to be recorded as analysis data.

DESCRIPTION OF THE PREFERRED EMBODIMENTS

FIG. 1 illustrates the principle structure of an ion micro-analyzer according to an embodiment of this invention. The analyzer according to this invention consists, when loosely stated, of an ion beam generator system for producing a primary ion beam I_p for irradiating a sample for analysis, an ion beam scanning system for planely scanning the sample surface with the primary ion beam I_p , an analysis point display system for displaying the image of secondary electrons emitted from the sample surface, a mass spectrometer system for performing a mass-spectroscopic analysis of the secondary ion beam I_s emitted from the sample surface, a scanning signal generator system for synchronously controlling the ion beam scanning system and the analysis point display system, a mass-scanning system for mass-scanning the mass spectrometer system, an analysis instruction signal generator system for initiating the mass spectrometer system, a data-recording system for recording analysis data, and other accessories.

A more concrete structure of these fundamental components and the operations thereof will be described in detail hereinbelow.

In FIG. 1, the ion beam generator system consists of an ion source 1, a mass separator 2, a focusing lens 3 etc. The ions emitted from the ion source 1 (for example, a duoplasmatron) are separated according to their mass-to-charge ratio (m/e values) by the magnetic type mass separator 2, and only such ions having a specified

m/e value are taken out of a slit. The ion beam taken out in this way is finely collimated by the focussing lens 3 and forms a primary ion beam I_p , which hits a small surface portion of a sample 5.

5 The ion beam scanning system consists of a pair of horizontal deflection electrode plates 4X and a pair of vertical deflection electrode plates 4Y. These deflection plates receive scanning signals e_x and e_y (see FIG. 2 (f) and (c)) from the scanning signal generator system described hereinbelow and scan the irradiation spot of the primary ion beam I_p planely over the sample surface. Here, the primary ion beam I_p is not continuously scanned, but the irradiation spot is made to fix at an arbitrary point on the sample surface for a constant time during scanning. Namely, the plane scanning of the irradiation spot and the fixing of the irradiation spot at a point on the sample surface are done alternately.

10 The analysis point display system consists of a secondary-electron detector 9 and a Braun tube oscilloscope 11. The detector 9 detects secondary electrons e emitted from the sample surface and the output signal E_e (FIG. 2(g)) is applied to an intensity modulation terminal 12 of the oscilloscope 11 to thereby display an image of secondary electrons from the sample surface as shown in FIG. 3. The electron beam e_o for display on the oscilloscope 11 is swept planely in synchronization with the scanning of the primary ion beam I_p . Thus, the same sweeping signals (or proportional signal voltages) as the scanning signals e_x , e_y (FIG. 2(f) and (c)) applied to the pairs of deflection plates 4X and 4Y of the ion beam scanning system are applied to pairs of horizontal and vertical deflection electrode plates 13X and 13Y of the oscilloscope 11. Accordingly, an image of secondary electrons from the sample as shown in FIG. 3 appears on the screen of the oscilloscope 11. The position of the fixed irradiation spot when the primary ion beam is fixed at a point for some constant time during scanning is displayed in the form of a brilliant point on the secondary electron image.

15 The mass spectrometer system comprises an energy selector 6, a magnetic field 7 for mass spectrometry, an ion collector 8 etc. In this system, the secondary ion beam I_s emitted from the analysis point is energy-analyzed into a beam of a definite energy by the energy selector 6 and injected into the magnetic field 7. The incident ions are mass-separated according to their m/e values and ions of different m/e values are detected 20 sequentially by the ion collector 8. For this purpose, a scanning-type magnetic field is used as the magnetic field 7. This magnet receives a mass scanning signal e_s (FIG. 4(e)) from the mass scanning system and the excitation current for this analyzer magnet is changed in 25 correspondence with the variation in the signal voltage, to facilitate mass scanning.

20 The scanning signal generator system consists of saw-tooth voltage generators 20 and 30 for scanning an ion beam, rectangular voltage generators 21 and 31 for setting an analysis point, variable-voltage DC voltage sources 22 and 32 for setting the rectangular voltages, and adders 23 and 33 for superposing signals. In this embodiment, a horizontal scanning signal e_x (FIG. 2(f)) is obtained by adding the output signal E_x (FIG. 2(d)) from the saw-tooth voltage generator 20 and the output voltage V_x (FIG. 2(e)) from the rectangular wave voltage generator 21 in a time relationship as

shown in FIG. 2 using a circuit changing switch 23. The vertical scanning signal e_y (FIG. 2(c)) is obtained by adding the output signal E_y (FIG. 2(a)) from the saw-tooth voltage generator 30 and the output signal V_y (FIG. 2(b)) from the rectangular voltage generator 31 in a time relationship as shown in FIG. 2 by use of a circuit changing switch 33. The rectangular voltage generators 21 and 31 receive output voltages from the variable DC voltage sources 22 and 32 and produce rectangular voltages V_x and V_y having the same voltage values. Thus, the magnitude of the rectangular voltage V_x and V_y may be changed arbitrarily. The horizontal and vertical scanning signals e_x and e_y obtained in this way are applied not only to the pairs of horizontal and vertical deflection electrode plates 4X and 4Y of the ion beam scanning system, but also to the horizontal and vertical deflection plates 13X and 13Y of the oscilloscope 11. Thus, the primary ion beam I_p and the image electron beam e , are scanned synchronously.

The mass scanning system consists of a saw-tooth voltage generator 40 for slow scanning, a step voltage generator 41 for fast jump scanning, a variable DC voltage source 42 for setting the value of the step voltage and an adder 43 for adding signal voltages. The mass scanning signal e_z (FIG. 4(e)) is obtained by adding the output voltage E_b (FIG. 4(d)) from the step voltage generator 41 and the output voltage E_z (FIG. 4(c)) from the saw-tooth voltage generator 40 with the adder 43. The excitation current flowing through the magnet for the analyzer magnetic field 7 is controlled in correspondence with the mass scanning signal e_z and thus mass scanning is performed. In this case, mass scanning is done selectively only for a plurality of ion peaks having specific mass numbers. Therefore, each step voltage of the output voltage E_b from the step voltage generator 41 is made to be freely adjustable by changing the setting voltage for each step of the variable DC voltage source 42.

The analysis-instruction-signal generator system consists of a pulse generator 50 and a button switch 51. When the button switch 51 is pushed (switched on), the analysis initiating pulse P_s (FIG. 6(c)) is sent out from the pulse generator 50. The pulse P_s is sent to the saw-tooth voltage generator 40 and the step voltage generator 41 of the mass scanning system to initiate mass scanning. The signal is also sent to the other circuit elements to adjust the timing of each circuit in operation.

The data-recording system consists of a multichannel digital printer 19 and desired data processing circuits connected to each recording channel. Namely, there is connected to a recording channel 18 for an ion peak display an ion collector output display circuit 15, a peak value read-out circuit 16 and an A - D converter 17. Each peak P_1 , P_2 , P_3 and P_4 of the output signals I_i (FIG. 4(f)) from the ion collector 8 is displayed in the form of a mass spectrum through the display circuit 15, the peak value R_i (FIG. 4(g)) is read out by a read-out circuit 16, and the peak values R_{i1} , R_{i2} , R_{i3} and R_{i4} are converted into digital quantities by the A - D converter 17 and displayed in a digital form in the recording channel 18. To a recording channel 47 for mass number display are connected a step voltage read-out circuit 44, a mass number display circuit 45 and an A - D converter 46. The voltage value at each step of the

step voltage E_b (FIG. 4(d)) generated by the step voltage generator 41 is read out by the read-out circuit 44 and the mass number (m/e value) corresponding to the voltage at each step is displayed by the display circuit 45. The voltage value at each step is further converted into a digital quantity corresponding to its m/e value by the A - D converter 46 and displayed in a digital form in the recording channel 47. Thus, an ion peak value R_i and the corresponding mass number (m/e value) are simultaneously recorded in the printer 19. The printer 19 further comprises recording channels for 26 and 36 for displaying the position of the analysis point corresponding to the analysis data. The recording channel 26 records the rectangular voltage V_x which displays the horizontal position of the analysis point and the recording channel 36 records the rectangular voltage V_y which indicates the vertical position of the analysis point. Thus, the horizontal position recording channel 26 comprises a rectangular voltage read-out circuit 24 and an A - D converter 25. The read-out circuit 24 reads out the rectangular voltage V_x at the time of analysis and the read-out voltage is then converted into a digital quantity by the A - D converter 25 and displayed by the recording channel 26 in a digital form. Similarly, the vertical position recording channel 36 comprises a rectangular voltage read-out circuit 34 and an A - D converter 35. The circuit 34 reads out the rectangular voltage V_y at the time of analysis, and the voltage is then converted into a digital quantity by the A - D converter 35 and displayed in a digital form in the recording channel 36. In order to distinguish between analysis data for a plurality of analysis points, the printer 19 comprises a channel 53 which records a number n indicating the order of setting the analysis points. This channel 53 counts the number of analysis instruction signals P_s with the counter 52 and displays the number n in a digital form.

Thus, the printer records not only the analysis data R_i for respective analysis points and m/e values, but also the number n of the analysis point and the voltage values V_x and V_y of the deflection voltages.

The analysis instruction signal P_s is set to the read-out circuits 16, 24, 34 and 44 to adjust the timing of signal reading. Thus, these circuits read the voltage values of signals at the time of analysis (at the time of mass-scanning).

The ion beam generator system, the ion beam scanning system, the parts composing the mass spectrometer system, the sample, the secondary-electron detector and so forth are contained in an appropriate evacuation system 10 and maintained in a suitable reduced-pressure state.

The specific composition of the device according to this invention has been described hereinabove. Now, the procedures of analysis and the performances of the device when analyzing a sample with the device of this invention will be described.

Let the sample surface be composed of B(boron), Al(aluminum), Si(silicon) and Ge(germanium) and these four components be distributed in a solid-state sample as shown in FIG. 3. Assume further that the sample is fixed at a predetermined position for ion beam irradiation. When the ion beam generator system and the scanning signal generator system are operated under this condition, the ion beam I_p is scanned

horizontally (in a direction of V_x axis in FIG. 3) with a frequency t_1 by a horizontal frequency t_1 by a horizontal scanning signal e_x (FIG. 2(f)) in a time interval t_2 shown in FIG. 2 and the ion beam I_b is deflected slightly in a vertical direction (direction of V_y axis in FIG. 3) by a vertical scanning signal e_y (FIG. 2(c)). Thus the beam scans a limited region of a sample planely within a time interval t_2 . The size of the scanned region depends on the peak values of the beam deflecting saw-tooth voltages E_x and E_y . The relationship between the size of the scanned region and the magnitudes of the ion beam deflecting voltages E_x and E_y is shown in FIG. 3.

The amount of secondary electrons emitted from the sample surface by scanning changes with the change of the sample composition along the scanning line of the ion beam, and the output signal E_e (FIG. 2(g)) from the secondary-electron detector 9 changes thereby, now, the output signal E_e from the secondary-electron detector 9 is added to the intensity modulation terminal 12 of the oscilloscope 11 swept synchronously with the scanning of the ion beam I_b by the scanning signals e_x and e_y , so that a secondary-electron image of the sample surface as shown in FIG. 3 appears on the fluorescent screen 14 of the oscilloscope. This secondary-electron image naturally represents the component distributions in the sample surface.

After the first plane scanning ends after a time interval t_2 , the ion beam irradiation spot is fixed at a point on the sample surface for the subsequent time interval t_o , the point on the sample being determined by the magnitudes of the rectangular voltages V_x and V_y . The relationship between the position of the fixed irradiation spot and the ion deflection voltages V_x and V_y is shown in FIG. 3. In the time interval t_o , the sweeping of an electron beam for image display e_o in the oscilloscope is stopped and the more brilliant point is displayed at the fixed irradiation position on the secondary electron image. This brilliant position on the secondary-electron image naturally corresponds to the position of a fixed irradiation spot on the sample surface.

Further, the plane scanning of the ion beam and the fixed position irradiation are repeated alternately with a time frequency of T_o as shown in FIG. 2, so that the secondary-electron image of the sample surface and the brilliant point corresponding to the fixed irradiation spot are displayed at all times on the fluorescent screen of the oscilloscope 11. Accordingly, the position of the fixed irradiation spot of the ion beam on the sample surface can be constantly monitored by observing the position of the brilliant point on the secondary electron image.

Now, if the time interval t_1 for horizontal scanning of the ion beam is 0.001 second and the number of scanning lines is 100, then the time t_2 needed for one vertical scanning (the time needed for one plane scanning) is 0.1 second. Further, if the time t_o for fixed point irradiation of the ion beam is 0.025 second which is one-fourth of the time t_2 , the time interval T_o for repetitive scanning becomes 0.125 second. If the afterglow time of the fluorescent screen of an oscilloscope is made equal to or longer than the time interval T_o , the secondary-electron image of a sample surface is ceaselessly displayed. Since the secondary-electron image is static, no trouble occurs in observing the sample surface even if the afterglow time of the fluorescent screen

is made sufficiently long. Thus, it is possible to make the time t_o for fixed irradiation of the ion beam as long as desired. For example, when the afterglow time is 5 seconds, T_o is made to be 5 seconds. The plane scanning time t_2 and the fixed irradiation time t_o can be suitably chosen within this time interval. For example, when the relation $t_o = \frac{1}{4}t_2$ holds, $t_o = 1/5T_o = 1$ second, and when $t_2 = 0.1$ second = constant, $t_o = 4.9$ seconds. Thus, by making the afterglow time of the fluorescent screen of an oscilloscope sufficiently long, the time t_o for fixed irradiation of an ion beam may be set relatively freely. It is to be noted that the time t_o is set by considering the relationship with the time t necessary for the mass-scanning described hereinbelow. Such a relationship in time is obtained by synchronously controlling the saw-tooth voltage generators 20, 30 and the rectangular voltage generators 21, 31.

When a secondary-electron image of a sample surface is displayed, the analysis point is selected by observing the image. Namely, in doing an analysis, it is necessary to select such a position as requires minimum operations for analysis. In the device according to this invention, the selection of an analysis point for mass-spectroscopic analysis is easily done because the secondary-electron image represents in itself a distribution of compositions in the sample surface as shown in FIG. 3. For example, when the composition distribution on the sample surface is as shown in FIG. 3, it will be easily understood that a plurality of analysis points need not be selected in a region consisting of a single component, and that it is appropriate to choose an analysis point near the boundary of the respective regions. Thus, the selection of an analysis point is facilitated by displaying a secondary-electron image on an oscilloscope. Here, it is assumed that the points $n = 1 \approx 8$ in FIG. 3 are chosen as analysis points.

After the analysis points are selected in this way, a mass-spectroscopic analysis is done for each point sequentially. For this purpose, the fixed irradiation spot of an ion beam must be made to coincide with the position of a desired analysis point. In the device of this invention, this operation is the same as the operation of moving the brilliant point on the secondary-electron image to the position for analysis (the point corresponding to the analysis point on the sample). Accordingly, this operation is performed by manually adjusting the output voltages from the variable DC voltage sources 22, 32 so as to make the brilliant point coincide with the position of the desired analysis point while observing the secondary-electron image. Namely, by adjusting the output voltages from the variable DC voltage sources 22 and 32, the rectangular voltages V_x and V_y are made to coincide with the deflection voltages for an ion beam corresponding to the desired positions of analysis. In this way, the setting of the ion beam irradiation spot to a desired analysis point can be done accurately and quickly. In this case, the setting is further facilitated if horizontal and vertical scales are provided on the fluorescent screen of an oscilloscope to make it possible to read the position of an arbitrary point on the secondary-electron image and the output voltages from the variable DC voltage sources 22 and 32 are made readable with a voltmeter comprising corresponding scales. Namely the fixed irradiation spot of an ion beam may be fitted to the analysis point more

easily by measuring the position of the desired analysis point on the secondary-electron image with a scale provided to the fluorescent screen and adjusting the output voltages from the voltage sources 22 and 32 so to make the indicator of each voltmeter coincide with the corresponding position on the scale.

After the fixed irradiation spot of an ion beam is made to coincide with the desired analysis point, a mass-spectroscopic analysis on this point is started. The start instruction is made by pushing a button-switch 51 after it is verified by observing the secondary-electron image that the fixed irradiation spot coincides with the analysis point. Namely, when the switch 51 is closed, an instruction pulse P_s (FIG. 6(c)) is sent out from the pulse generator 50. The pulse P_s is sent to the mass scanning system to start mass-scanning and simultaneously it is sent to the scanning signal generator system to increase the time for fixed irradiation of an ion beam.

The saw-tooth voltage generator 40 and the step voltage generator 41 of the mass scanning system receive the instruction pulse P_s for analysis, and operates in a way to generate a mass scanning signal e_s (FIG. 6(d)) from the time when the fixed irradiation of an ion beam is started as shown in FIG. 6. The rectangular voltage generators 21 and 31 of the scanning signal generator system receives the instruction pulse P_s for analysis and increases the time for the subsequent fixed irradiation with an ion beam. Namely, as shown in FIGS. 6(a) and 6(b), the time interval of the rectangular portions of the ion beam scanning signal voltages e_x and e_y (time for the fixed irradiation with an ion beam) is changed from t_0 before analysis to a time interval T at the time of analysis.

The above description refers to a case where the time interval for the fixed irradiation with an ion beam is increased to T ($T = t \geq t_0$) only at the time of analysis. This case takes into account the fact that a desired mass-spectroscopic operation may not be performed within the time interval t_0 for the fixed irradiation with an ion beam before analysis (for example, when t_0 is 0.1 second and a mass-spectroscopic analysis requires a time t of several seconds). However, when required mass-spectroscopic operations can be performed satisfactorily within the time interval t_0 i.e. $t \leq t_0$) by making the time t_0 for the fixed irradiation sufficiently long (for example, several seconds), it is not necessary to increase the time T for the fixed irradiation at the time of analysis (or it is sufficient to make $T=t_0$).

The required mass scanning is done within the time interval T during which a fixed analysis point (for example, point $n = 4$ in FIG. 3) is irradiated with an ion beam. The scanning is done only for such peaks as have required mass numbers i.e. ion peaks of boron, aluminum, silicon and germanium having mass numbers (m/e) of 10, 27, 28 and 72 in the examples shown in FIGS. 3 and 4). For this purpose, slow scanning intervals S_1, S_2, S_3 and S_4 (interval width $\tau = T/4$) for the scanning signal e_s are set in advance so that only the desired ion peaks P_1, P_2, P_3 and P_4 may be observed with an ion collector. The mass number of the ion peak measured with the ion collector within each slow scanning interval of the scanning signal is determined approximately by the potential E_{b1}, E_{b2}, E_{b3} or E_{b4} , which is a voltage at each step of the step voltage E_b .

Each step voltage is supplied from each setting terminal of the variable DC voltage source 42. Thus, an ion beam having an arbitrary mass number can be selectively measured by adjusting each terminal voltage of the variable DC voltage source 42. It is preferable in this case to make the terminal voltages of the voltage source 42 readable in the form of a mass number. A case where only four ion peaks are observed has been described hereinabove, but it is needless to mention that an arbitrary number of ion peaks may be selectively measured by changing the step numbers of the step voltage E_b .

By the mass scanning described above, the ion peaks P_1, P_2, P_3 and P_4 as shown in FIG. 4(f) are detected by the ion collector 8, these peaks are displayed in the form of a mass spectrum by the display circuit 15, and the peak values R_{11}, R_{12}, R_{13} and R_{14} (FIG. 4(g)) are read out by the read-out circuit 16 and displayed sequentially in a digital form by the channels 18 of the printer 19.

In order to display the mass numbers (m/e values) corresponding to these peaks, voltages at respective steps $E_{b1}, E_{b2}, E_{b3}, E_{b4}$ (FIG. 4(d)) of the step voltage E_b are read out by the read-out circuit 44, converted into their corresponding mass numbers (m/e values) and displayed sequentially in a digital form by the channels 47 of the printer 19.

Further, in order to display which analysis datum corresponds to a particular analysis point, the values of rectangular voltages V_x and V_y (FIG. 4(a) and (b)) within the time T , during which the fixed analysis point is irradiated with an ion beam, are read out by the read-out circuits 24 and 34 and displayed in a digital form by the channels 26 and 36 of the printer 19.

The channel 53 of the printer 19 digitally displays the number of pulses counted by the counter 52 as the number of the analysis points.

After an analysis is completed in this way for a particular analysis point, all the circuits are reset immediately and return to the state of non-analysis as shown in FIG. 6. By repeating these processes, a mass-spectroscopic analysis is done for a plurality of analysis points as required. FIG. 7 shows the time relationship between the instruction pulse P_s for analysis at each analysis time, the corresponding rectangular voltages V_x and V_y , the step voltage E_b corresponding to the analysis point and the ion peak display signal R_i . These signal voltages are read out and digitally displayed by the printer 19 at the time of analysis. FIG. 5 shows an example of analysis data printed out by the printer 19 and the number at each channel corresponds to each signal voltage shown in FIG. 7.

In the analysis data (FIG. 5) obtained in this way, the fourth analysis data ($n = 4$) correspond to the analysis point of $n = 4$ shown in FIG. 3 (ion beam deflection voltages $V_x = 300$ V and $V_y = 200$ V). It is understood that the ion peak values are 35 mV for B^{10} of $m/e = 1$, 15 mV for A^{27} of $m/e = 27$, 50 mV for Si^{28} of $m/e = 28$ and 0 mV for Ge^{72} of $m/e = 72$.

As has been fully described hereinabove, the analysis point can be selected by observing the secondary-electron image of a sample surface in the device of this invention so that the selection of unnecessary analysis points and thus unnecessary operations can be avoided. Further, since the position of the fixed irradiation spot

of an ion beam can be determined accurately on the secondary-electron image of the sample surface, the operation of making the irradiation spot coincide with the analysis point is quite simple and accurate. Further, not only analysis data, but also the position of each corresponding analysis point is automatically recorded. Thus, the relationship between each analysis datum and each analysis point becomes apparent so that erroneous treatments of analysis data may be avoided and the accuracy of analysis may be enhanced.

Accordingly, the device of this invention enables an accurate and fast analysis of a small region in a solid-state sample and has great practical advantages.

We claim:

1. In an ion micro-analyzer having means for projecting a primary ion beam on a surface of a sample to be analyzed, electric deflecting means for scanning the sample surface with the primary ion beam, means for detecting secondary electrons emitted from the sample surface in response to the irradiation with the primary ion beam, an oscilloscope for displaying the secondary-electron image of said sample surface, which is swept synchronously with the scanning of the primary ion beam and which is intensity-modulated by the

output signal from said detecting means, and mass-spectroscopic analyzer means for analyzing secondary ions emitted from a fixed position on the sample surface by the irradiation with the primary ion beam, the improvement which comprises

- 5 a saw-tooth voltage generator for generating a saw-tooth voltage,
- 10 a rectangular voltage generator for generating a rectangular voltage,
- 15 means for adding the rectangular voltage to the trailing edge of the saw-tooth voltage, thereby producing a scanning signal consisting of both voltages, means for applying the scanning signal to said electric deflecting means and said oscilloscope, and means for adjusting the rectangular voltage.
- 20 2. An ion micro-analyzer according to claim 1, which further comprises means for deriving the rectangular voltage from said rectangular voltage generator, means for determining the fixed position of the primary ion beam on the sample surface from the derived rectangular voltage and means for recording said position as well as the analysis data obtained by said mass-spectroscopic analyzer means.
